UNITED STATES PATENT OFFICE

JOHN H. HUDSON, OF ARDMORE, OKLAHOMA

WATER HEATER AND STEAM CONDENSER

Application filed December 7, 1928. Serial No. 324,382.

My invention relates to improvements in water heaters and steam condensers, and it consists in the combinations, constructions, and arrangements herein described and 5 claimed.

An object of my invention is to provide a device for preheating water for a steam boiler by utilizing the exhaust steam from the steam-driven engine, pump, or the like. 10 A further object of my invention is to provide a device of the type described by means of which the water may be heated and steam condensed simultaneously, and both the heated water and the steam condensate being used to replenish a boiler with water. 15

A further object of my invention is to provide a device of the type described which may be easily constructed at the place where it is to be used.

20 A further object of my invention is to provide a device of the type described embodying a water heater and steam condenser in a single unit.

25 A further object of my invention is to provide a device of the type described which may be conveniently transported from one location to another without damaging its structure or impairing its utility.

30 Other objects and advantages will appear in the following specification, and the novel features of the invention will be particularly pointed out in the appended claims.

35 My invention is illustrated in the accompanying drawings, forming part of this application, in which

Figure 1 is a top plan view of my device.

Figure 2 is a horizontal sectional view of my device, and

40 Figure 3 is an end elevation of my device.

45 In carrying out my invention, I provide two spaced-apart pipelike members 1 and 2 of the same diameter and length. It is preferable to have the members 1 and 2 of large diameter, such as oil well casing or the like. The members 1 and 2 are connected at one end by a pipelike member 3 which is of the same diameter as the members 1 and 2. The members 1, 2, and 3 are joined at 4, forming a U-shaped unit.

50 The ends 5 and 6 of the members 1 and 2

are closed by end walls 7 and 8. A plurality of pipe coils 9 and 10 are disposed in the members 1 and 2, respectively. The pipe coil 9 is provided with an inlet pipe at 11 and is connected to the coil 10 by means of a pipe 12. The coil 10 has an outlet pipe provided at 13. Supports 15 are disposed in the members 1 and 2 for holding the coils 9 and 10 in place. The supports 15 are rigidly held in place by any suitable means, such as welding. A brace connector 16 is disposed between the members 1 and 2 adjacent the ends 5 and 6 thereof to securely hold the members 1 and 2 in their proper position. The brace 16 may be constructed of pipe of the same diameter as the members 1 and 2 and may be welded or otherwise suitably attached.

55 Inlet pipes 19 are connected to the member 1 and are in communication with a compartment 17. An outlet pipe 20 is attached to the member 2 and is in communication with a compartment 18. A steam condensate pipe 21 is attached to the member 2 in a manner like or similar to that of the outlet pipe 20.

60 From the foregoing description of the various parts of the device, the operation thereof may be readily understood. The U-shaped unit is filled with steam by means of the steam pipes 19 leading from the exhaust chamber 22 of a steam engine, steam pump, or the like. After the steam has filled the U-shaped unit, it may pass through the outlet pipe 20—thus 65 providing a continuous flow of steam through the U-shaped unit. Cold water from any source, such as a pump 24, is forced into the coils 9 and 10 by means of the outlet pipe 11, passes through the coils, and then passes outwardly through the pipe 13. The water is heated by reason of its contact with the steam heated coil pipes 9 and 10. The heated water passing through the outlet pipe 13 is directed to a steam boiler 23 where it is readily converted into steam because of its temperature.

70 A condensate is formed by reason of the steam contacting with the cold water coils. The condensate thus formed passes through the pipe 21 and may be either returned to the 75

boiler, since it is of a comparatively high temperature or it may be discarded.

It should be understood that the members 1, 2, 3, and 16 may be formed of oil well casing. The coils may be formed of pipes connected by means of elbows and disposed in their respective positions in the U-shaped casing. The various connected members may be secured in place to form seal-tight connections by any suitable means, such as welding:

I claim:

1. A device of the type described comprising a U-shaped casing formed from a pair of tubular portions arranged in parallelism, a tubular element for connecting the portions together, and a coil disposed within each of the portions and being operatively connected.
2. A device of the type described comprising a casing formed from a pair of tubular portions, a tubular element for connecting said portions, supporting members disposed within each of the tubular portions and being provided with openings, and a coil disposed within each of the tubular portions and being disposed within the openings in the supports, said coils being operatively connected and being provided with an inlet pipe and an outlet pipe.
3. A device of the type described comprising a casing formed from a pair of tubular portions, a tubular element for connecting said portions, supporting members disposed within each of the tubular portions and being provided with openings, a coil disposed within each of the tubular portions and being disposed within the openings in the supports, said coils being operatively connected and being provided with an inlet pipe and an outlet pipe, an inlet steam pipe entering one of said tubular portions, and an outlet steam pipe communicating with the other of said tubular portions.
4. A device of the type described comprising a casing formed from a pair of tubular portions, a tubular element for connecting said portions, supporting members disposed within each of the tubular portions and being provided with openings, a coil disposed within each of the tubular portions and being disposed within the openings in the supports, said coils being operatively connected and being provided with an inlet pipe and an outlet pipe, said supports being narrower than the diameter of the tubular portions, an inlet steam pipe communicating with one of the tubular portions, and an outlet steam pipe communicating with the other of said tubular members.

Signed at Ardmore, in the county of Carter and State of Oklahoma this 17th day of November, A. D. 1928.

JOHN H. HUDSON.
